Primary Examiner — Stacia A Cadmus(74) *Attorney, Agent, or Firm* — Ahn IP Law(57) **CLAIM**

The ornamental design for an automotive wheel, as shown and described.

DESCRIPTION

FIG. 1 is a perspective view of an automotive wheel; and, FIG. 2 is a front view of the automotive wheel.
The broken lines shown in the figures are included for the purpose of illustrating the environment and form no part of the claimed design.
